CLETUS CLINTON VAN VOORHIS, OF WILKINSBURG, PENNSYLVANIA, ASSIGNOR TO
WESTINGHOUSE LAMP COMPANY, A CORPORATION OF PENNSYLVANIA.

GROUND DETECTOR.

Application filed December 13, 1919. Serial No. 344,611.

My invention relates to ground detectors and particularly to vacuum-tube ground detectors.

One object of my invention is to provide 5 an indicating device that shall be adapted to indicate when any one of the bus-bars, to which it is connected, becomes grounded.

Another object of my invention is to provide 10 an indicating device, of the above indicated character, that shall be visible from a distance.

A further object of my invention is to provide 15 an indicating device, of the above indicated character, that shall be compact and simple, and inexpensive to construct.

In practicing my invention I provide a 20 glass receptacle comprising a central bulb and a plurality of radially disposed bulbs that are connected to the central bulb by tubes. An electrode is sealed in each bulb. The electrode in the central bulb is connected to the ground and each of the remaining electrodes is connected to a point on a corresponding bus-bar insulator that is immediately 25 beyond the section adjacent the supporting framework. The insulators that support the bus-bars comprise pluralities of sections that are so disposed between the bus-bars and the supporting frame as to 30 constitute, in effect, pluralities of condensers connected in series therebetween. Since the supporting frame is normally grounded, the insulator sections that are adjacent the frame constitute condensers connected between the electrodes of the central and the 35 radial bulbs, respectively.

The gas is withdrawn from the receptacle 40 in order to create a low-pressure partial vacuum therein. The receptacle is, in effect, a plurality of Geissler tubes that have a common bulb and extend radially therefrom. Various gases may be used for different colored indications that may be effected in the several tubes by the condenser 45 discharge of the insulator sections connected thereto. Normal conditions are indicated by a glow effected by discharges through the tubes.

A ground on any bus-bar eliminates the 50 potential gradient across the insulator that supports the bus-bar and, therefore, the potential becomes the same on both sides of the section that is used as a condenser for effecting discharges through the tube. The

elimination of the potential gradient eliminates the discharge and, consequently, the attendant glow in the tubes. The bus-bar that is affected may thus be readily indicated by the absence of glow in the tube that is connected thereto. 55

Figure 1 is a front elevational view of a 60 ground detector embodying my invention; Fig. 2 is a side elevational view, of the detector shown in Fig. 1, and Fig. 3 is a diagram showing the connections of the ground 65 detector.

A ground detector 1 comprises a central bulb 2 and a plurality of radially disposed bulbs 3, 4, and 5, connected thereto by a plurality of tubes 6, 7 and 8. Electrodes 9, 10, 70 11 and 12 are sealed in the glass walls of the respective bulbs 2, 3, 4 and 5. The central bulb electrode 9 is connected to ground 13 and the electrodes 10, 11 and 12 of the radially disposed bulbs 3, 4 and 5 are connected to points 14, 15 and 16 between the ends of the insulators 17, 18 and 19, respectively. The insulators 17, 18 and 19 support the bus-bars 20, 21 and 22, respectively 75 of a polyphase circuit, and are mounted on 80 a supporting framework 23, that is connected to the ground 13.

Normal conditions in the circuit are indicated by a marked glow in the tubes 6, 7 and 8 that join the central bulb 2 and the 85 radially disposed bulbs 3, 4 and 5. This glow being caused by the drop in potential across the portions of the insulators between the points 14, 15 and 16 and the ground and, consequently, across the respective tubes. 90 That is, portions of the insulators constitute condensers across which the tubes are connected. A ground on any bus-bar, such as might occur through a broken and grounded line or through a broken insulator will 95 destroy the potential gradient across the insulator that supports the corresponding bus-bar, by equalizing the bus-bar and the framework potentials. The absence of potential difference across the insulator sections 24, 25 and 26 precludes any glow in the tubes connected thereacross. The faulty bus-bar or line may thus be readily indicated. 100

Although I have shown only one form of 105 ground detector embodying my invention, I do not wish to be limited to the structure shown, as various modifications may be made

therein without departing from the spirit and scope of the invention, as set forth in the appended claim.

I claim as my invention:

- 5 In an alternating-current system, the combination with the conductors thereof and insulating members for the conductors, of a ground-detector comprising a vacuum receptacle having a central bulb and a plurality of
10 bulbs joined thereto, a plurality of

electrodes sealed in the respective bulbs, said electrodes being so electrically disposed as to include a portion of the respective insulating members between the central electrode and the respective radially disposed electrodes.

In testimony whereof, I have hereunto subscribed my name this 8th day of December 1919.

CLETUS CLINTON VAN VOORHIS.
